LIQUID FUEL BURNER

William Edward Taft, Athol, Mass., assignor to
The Silent Glow Oil Burner Corporation, Hartford, Conn., a corporation of Connecticut

Application April 15, 1929, Serial No. 355,966

11 Claims. (Cl. 158—87)

This invention relates to oil burners of the type having a base provided with annular fuel channels and perforated combustion tubes or chimneys which upstand above the base and surround the channels and between which combustion of the liquid fuel vapor and gas takes place. With the usual liquid fuel burner of this general type, a liquid fuel such as oil is maintained at a constant level within the fuel channels and is adapted to be continuously vaporized by the heat of combustion of the vapor in the space between the chimneys and above the channels. With this type of burner much trouble is experienced in the formation and collection of carbon in the fuel channels due to the breaking down or decomposition of the oil as it vaporizes resulting in the clogging of the channels and the fuel passages communicating therewith and necessitating frequent, as weekly, inspection and cleaning to maintain the burner in operative condition.

An object of the present invention is to provide an oil burner of the general type above set forth which is so arranged that it is practically free from carbon deposits so that it can remain in good operative condition for long periods of time.

A further object of the invention is the provision of a burner having an annular fuel chamber with combustion tubes or chimneys extended upwardly therefrom and so arranged that combustion of the fuel is caused to take place within the chamber and below the chimneys, thereby heating the walls of the combustion chamber to such a high degree that vapor only can exist in the chamber.

In carrying out the above object of the invention, I provide an annular fuel chamber which is large in its radial dimension as compared with heretofore common practice. I also provide a cover for the major portion of the radial extent of the chamber leaving only an annular opening at one side of the chamber which is small in radial extent as compared with the radial extent of the chamber. Such construction is a further object of the invention.

A further object of the invention is the provision of an oil burner having a base provided with a plurality of radially-spaced, concentric, annular fuel channels with annular air passages between the channels and with an air passage within the innermost channel, and combustion tubes or chimneys carried by the walls of the channels and upstanding therefrom, the base having vapor passages which connect the con-

centric channels, the innermost channel being substantially larger in radial extent than the outer channels and receiving the fuel.

A further object of the invention is the provision of electrical high tension igniting means for the burner and especially means wherein the ignition electrode is removable from its operative position along with one of the combustion tubes.

Another object is the provision of electrical heating means for the burner and the fuel therein.

A still further object of the invention is the provision of mounting means having a plurality of burners of the type above described wherein the burners can be readily removed from operative position on the mounting means and restored thereto and held in a predetermined position without the necessity for employing set screws or bolts or special tools.

A yet further object is generally to improve the construction and operation of oil burners.

Fig. 1 is a side elevation, partly in section, showing a plurality of oil burners on a supporting mounting within a furnace.

Fig. 2 is a sectional elevation taken along lines 2—2 of Fig. 3.

Fig. 3 is a plan view of the burner of Fig. 2, with all but the innermost combustion tube removed and with the cover of the innermost annular fuel channel broken away.

Fig. 4 is a plan detail of the supporting bracket for the burner.

Fig. 5 is an enlarged detail showing a portion of the bracket and a burner and illustrating particularly the manner in which the burner is connected with the bracket.

Fig. 6 is a sectional detail, taken along lines 6—6 of Fig. 2.

As here shown, the burner includes an annular cast iron base 10 having an outer annular fuel channel or chamber 12 provided with radially spaced upstanding bounding walls 14 and 16, and an inner annular fuel channel or chamber 18 which is concentric with said outer channel 12 and has upstanding radially-spaced side walls 20 and 22. The channels are integrally connected by a plurality of spaced ribs 24 which serve to hold said channels in radially spaced relation and also to provide an annular air channel 26 of substantial radial extent between the fuel channels. The ribs 24 are provided with horizontal, radially-extended ducts or fuel passages 28 which are of substantial cross-section and the bottoms of which are substantially in horizontal line with

the bottoms of the fuel channels 12 and 18 and serve to connect said channels in a plurality of points around the circumferential extents thereof. The annular wall 22 of the innermost channel 18 constitutes a neck which surrounds a large air opening or passage 30.

A vertical fuel pipe 32 is extended through the bottom wall of the base 10 and terminates substantially flush with or somewhat above the bottom of the innermost channel 18 adjacent the inner wall 22.

In accordance with this invention, the innermost channel or chamber 18 is considerably wider or of greater radial extent or width than is usually the case and is greater in radial extent than the narrow outer channel 12. A removable cap or cover 34, composed of cast steel, has an annular recess 36 in its bottom face in which the upper end of the inner wall 22 is received and on the top of which wall said cap is seated removably. The peripheral edge 38 of said cap extends downwardly into the open portion of the annular channel 18 and horizontally thereover and its periphery is located in spaced connection relation with the outer wall 20 of said channel 18, thereby to provide a narrow annular vapor passage 40 that communicates with the interior of said channel or chamber 18 and is of considerably smaller radial extent or width than is said channel and is approximately as wide as the outer channel. Said cap 34 also overlies the open end of the fuel pipe 32. The walls 14, 16 and 20 and the peripheral edge 38 of the cap 34 are provided with seats 42 on which vertically-upstanding concentric and radially-spaced combustion tubes or chimneys 44, 46, 48 and 50, respectively, are seated removably. Said tubes thus form between them vertical annular combustion chambers 52 and 54 respectively which are located above and are in communication with the fuel channels 12 and 18 respectively. The tubes 46 and 48 cooperate to provide an annular air chamber 56 which is located between the adjacent combustion chambers. The combustion tube 50 surrounds the inner air chamber 56 which receives air through the neck 30 and the axially-aligned passage 60 in the removable cap 34. Said tubes are perforated throughout their axial and circumferential extent as is indicated best in Figs. 1 and 5, whereby air for combustion is drawn through the perforations into the vapor or combustion chambers 52 and 54 through said walls. A cover plate 62 is disposed upon the top of the innermost combustion tube 50 and has an outstanding ledge 64 that is seated on the end of said tube. Said cover 62 is connected by screws 66 with the cap 34 so that said cover, tube and cap can be withdrawn as a unit, thereby freely exposing the inner fuel channel 18. A ring 68 is received within the tubes 46 and 48 and forms a closure for the top of the air chamber therebetween and has outstanding flanges 70 which overlie and are seated upon the tops of said tubes. Said latter tubes and said outermost tube 44 can also be removed from the burner base upon need.

The outer periphery of the cover 62 is not in continuous peripheral engagement with the upper portion of the inner face of the tube 50 as it has been found that, with such continuous engagement, the expansion of the cover under heat permanently expands the top of the tube. Consequently the cover is provided with a few peripherally spaced projections 63 which engage the inner face of the tube at the top, there being clearance channels 63a between the projections. With this

arrangement, when the cover is heated and expands, the top of the tube is forced outwardly at the projections and draws into said channels, between said projections. As a consequence, while the tube is temporarily distorted, the material thereof is not put under such great strain as to destroy it permanently and, when the burner is turned off and the cover has cooled, the tube regains its cylindrical shape. The outer periphery of the cover-ring 68 is similarly provided with outstanding projections 69 which engage the inner face of the top of the tube 46, and clearance channels 69a between said projections, for the same purpose.

The burner base is supplied with fuel through the aforesaid pipe 32 which communicates, see Fig. 1, through a coupling 72 and a valve 74, with a pipe 76 that extends to a float valve 78 that in turn is connected to the main oil tank 80. The float valve is set in such elevated position with respect to the burner that the oil level therein comes about midway up the height of the fuel channels 12 and 18 of the burner.

When the burner is first started in operation, oil is in both of said channels to the same level. When the device is lighted the heat of initial combustion serves to vaporize the oil in the channels and supply more power for combustion. With the usual type of burner wherein the channels corresponding to the channels 12 and 18 are both of about the same radial extent, as the channel 12, oil remains continuously in both channels and boils therein for so long as the burner is in operation. Due to the continual presence and boiling of the oil in the channels, the oil is cracked and broken down or decomposed and carbon is deposited in the narrow channels, and especially in the innermost channel. With the construction here shown, however, this action does not take place. After the burner has been in operation for a short while, or until the parts have reached a constant temperature, it is found that there is no liquid oil present in the channels 12 and 18 and that there is strong combustion taking place within the channel 18 which causes the oil to vaporize immediately without depositing carbon and that the temperature of the cap and the walls of the channel 18 is too high to permit either oil or carbon to remain in the channel. The fuel vapors pass upwardly into the combustion chamber 54 and also through the passages 28 into the channel 12 and thence upwardly into the combustion chamber 52 and mix with air therein and are burned. The burning in these combustion chambers takes place more or less in the usual manner. Inspection of burners in operation indicates that strong combustion takes place and a relatively high temperature is generated under the cap 34 and in the channel 18. It is found that the cap 34 must be made of steel instead of cast iron as a cast iron cap has its lip or peripheral portion 38 burned away in less than a week of service, the burning progressing from the lower face of the cap. It is considered that the large width of the channel 18 combined with the cap 34 which covers the major portion of the top of the channel is effective in insuring combustion and freedom from carbon deposition in the channel 18. The passages 28 are large in cross section to distribute substantially uniformly in the outer channel 12 gases and vapors that are generated by the combustion in the channel 18 so that the supply of gas and vapor to both combustion chambers is practically the same.

The device is started in operation electrically.

- by means of a high tension conductor or ignition electrode 82 which is carried by an insulating bushing 84 secured in the removable cap 34 and extended horizontally through an opening in the 5 innermost combustion tube 50 and terminated in closely-spaced relation with the tube 48 so that a spark will jump from the outer end of said electrode to said tube, which constitutes the other terminal of the igniting means, thus to ignite the 10 combustible vapor in the vapor passage. The inner end of said ignition electrode is spaced above and is in close proximity with the upper end of a fixed conductor 86 which is secured to an insulating plate 88 carried by the burner base. 15 Said conductor 86 is connected to one terminal of a suitable high tension transformer (not shown) while the other high tension terminal of the transformer is grounded onto a part of the burner. Since the high tension conductor 86 is 20 not permanently connected with the ignition electrode 82, said electrode can be removed from the aforesaid relation along with the cap 34 and the associated combustion tube 50.

The fuel in the burner can be initially vaporized by means of an electric heating unit 90 in the form of a flat disc having metal walls which enclose the heating element, which unit is received upon the bottom wall 92 in heat-conducting relation therewith and under the inner fuel channel 18. The heating unit is held removably in the aforesaid relation by clips 94 which underlie said unit and are secured removably to lugs 96 which depend from the bottom wall of the burner base. The heating unit is required to be 35 in operation only long enough to vaporize oil for initial combustion and can thereafter be placed out of service.

Means are provided to support a plurality of burners within a furnace. Figs. 1, 4 and 5 illustrate supporting means for three burners. The supporting means includes a base 98 having feet 100 which are provided with leveling screws 102. A vertical shaft 104 upstands above said base and a supporting bracket 106 is slidable thereon and can be secured in any adjusted position thereon by screws 108. Said bracket 106 is provided with a plurality of, and, as here shown, three equi-angularly-spaced upstanding bosses 110 which have vertical passages 112 therethrough.

The base 10 of each burner is provided with a depending cylindrical lug 114 which fits within the passage 112, whereby the burner is supported removably in position. The boss 114 on the upper end thereof is provided with a laterally-extended lug or key 116 which fits into a horizontal slot 118 in the top face of the boss 110 thus locking the burner in fixed position against rotation. The slots are so arranged that, for the supporting bracket here shown, the burners are positioned equi-angularly apart.

The construction can be modified without departing from the spirit of the invention. For instance, the number of annular fuel channels can be increased, upon necessity, and need not be restricted to two as here shown.

I claim:

1. In a liquid fuel burner, a base having spaced upstanding side walls providing between them an annular fuel chamber, a cap removably seated upon the inner side wall, spaced combustion tubes carried respectively by the cap and said outer side wall and upstanding above and in communication with said chamber, a high tension conductor carried by and insulated from said base, and an insulated high tension electrode car-

ried by said removable cap having one end thereof disposed adjacent but free from connection with said conductor and having the other end extended through the combustion tube carried by said cap and into the space between said tubes and terminating in spaced relation with said other combustion tube. 5

2. A combustion tube burner having a base provided with a fuel channel, spaced perforated combustion tubes in upstanding relation to the base forming between them a combustion chamber having an air supply through the perforations in said tubes and opening at its bottom into said fuel channel, means to supply liquid fuel to said channel, electrical heating means associated with 10 said base but out of contact with said liquid fuel to preheat and vaporize said fuel by conduction through the walls of the base, and electrical igniting means to ignite the fuel vapor comprising a spark creating device immediately above said 15 fuel groove within and near the bottom of said combustion chamber and within the region of the air supply thereto.

3. A combustion tube burner having a base provided with a fuel channel, spaced perforated combustion tubes in upstanding relation to the base forming between them a combustion chamber having an air supply through the perforations in said tubes and opening at its bottom into said fuel channel, means to supply liquid fuel to said channel, electrical heating means to preheat and vaporize the fuel in said channel, and electrical igniting means to ignite the fuel vapor comprising a spark creating device in the combustion chamber within the region of the air supply 30 thereto. 35

4. A combustion tube burner having a combustion chamber, a base provided with a vaporizing chamber communicating with said combustion chamber, a removable cover for said vaporizing 40 chamber, and an electrical, fuel-igniting device supported by said cover.

5. A combustion tube burner having a base provided with a vaporizing chamber, means for supplying fuel to said vaporizing chamber, a removable cover for said chamber, and fuel igniting means comprising an electric, current-carrying device supported by and removable with said cover. 45

6. A burner having a base provided with an annular fuel channel, spaced, perforated combustion tubes in upstanding relation to the base and forming between them a combustion chamber above and communicating with the fuel channel, a structure removably resting on the walls 55 of the base interposed between the latter and one of the combustion tubes but providing a support for said tube, and electrical, fuel igniting means including a current-carrying member carried by said structure. 60

7. A burner having a base provided with an annular fuel channel, combustion tubes in upstanding relation to the base and forming between them a combustion chamber above and communicating with the fuel channel, electric, fuel igniting means including an igniting member positioned immediately above the fuel channel, a structure removably seated on the base and carrying said igniting member, a fixed terminal 65 for said member carried by the base outside of said annular channel, and a cooperating and registering movable terminal carried by and movable with said structure whereby, when said structure is applied to the base, said movable 70 75

- terminal is operatively related to said fixed terminal.
8. In a liquid fuel burner, a base having outer and inner spaced upstanding side walls providing an annular fuel channel therebetween; means to admit fuel to said channel, a cap seated removably upon said base, combustion tubes carried by said cap and said outer wall respectively on opposite sides of and upstanding above the top of said channel, an electric igniting member carried by said removable cap and located in the space between the tubes, a fixed terminal for said member, and a cooperating movable terminal carried by and removable with said cap.
9. A combustion tube burner having a base provided with an annular fuel channel, said burner having a combustion chamber above and communicating with the fuel channel, a structure removably resting on the walls of the base, and fuel igniting means comprising an electric current-carrying device carried by said structure and positioned in said combustion chamber immediately above said fuel channel.
10. A combustion tube burner having a base provided with an annular fuel channel, spaced perforated combustion tubes removably supported in upstanding relation on the base forming between them a combustion chamber provided

with an air supply through perforations in said tubes and opening at its bottom into said fuel channel, and electric fuel igniting means including an insulated electrode and means structurally uniting the same with one of said tubes and rendering it removable therewith, said electrode being positioned in said combustion chamber above the lowermost perforations in said tubes and in the region of air supply to said chamber, said burner presenting a companion electrode in spaced relation to said first electrode.

11. A burner having a base provided with an annular fuel channel, removable combustion tubes in upstanding relation to the base and forming between them a combustion chamber above and communicating with the fuel channel, fuel igniting means including an electrode projecting through but insulated from one of said combustion tubes and means structurally uniting said insulated electrode with said tube, rendering it removable therewith, said electrode being positioned in the space between said tubes, a companion electrode presented by the burner, a fixed terminal carried by the base for said first named electrode and positioned so that when said tube is positioned on the base, said first named electrode is operatively related to said fixed terminal.

WILLIAM EDWARD TAFT.
